(54) **KNIFE SHARPENER, & DOMESTIC GUARD**

(76) Inventor: **Walter Hunt**

Walter Hunt

Walter Hunt

The schedule referred to in these U. S. Patents & making, part of the same, containing a description of the goods of the said Walter Hunt himself of his improvement in a machine for sharpening, carving, planing & other edge tools that require a rough edge, determined the Compound Guard & Knife Sharpener.

The Compound Guard & Knife Sharpener is constructed as follows. The operators or sharpening rollers are made of hardened steel, about $\frac{1}{8}$ of an inch thick, & near the diameter of a half-penny, less or larger as the case may require, & with one corner, made sharp, for each wheel, or sharpener, in order to occupy less space in setting the sharpeners. They are cut down from the center of the center or the opposite sides of the wheel so as to allow the larger half of the rim to pass by each other about the eighth of an inch more or less as required. They may be set without bolting the rims, but require more thickness or space in the front of guard, where they are set. Therefore the front rims are preferable and are set in a manner to suit the guard. shank, & no hole or any other part or appendage, of a carving fork, & turn up joint, or center in slight margin, that in using, the center of friction will be distributed.

around the whole circumference of the sharpener. Where the "sharpening tools" are set in forks made for the purpose, they form a Guard & Sharpener being set in the neck of the fork which may be semi-cylindrical, or elevated on the table where the tools are set in. In order to set them to advantage in the common carving fork, the old guard may be removed, & a new one made of suitable thickness & size to receive the sharpener in an opening, or mortise cut thru the same, supported upon blocks with the lines as aforesaid partially passing each other. This mode of putting or attaching the sharpener to the "carving fork" instead of a stand, or other appendage, for plates, use although preferable, as it is always at hand, when wanted, in the act of carving. & the knife, becoming suddenly dull, which often occurs, the edge may be instantly restored without drawing the fork from its place, by passing the edge of the knife between the sharpener & one or both of the supports, they are descriptive, guard, in order to hold the sharpener firm, press down the guard, with the back of the carving knife, raising it with the same, reluctantly. The sharpening, Beleches, knives & other knives where the fork is not wanted, the sharpener may be set in a stand, just as handle, fixed in a stand, bench or otherwise as may be required, & suspended upon tenons in the fork.

The method of using is this, if you have the same in a handle or fork, they must be held

form, in one hand, the knife drawn with the edge between the fingers, the sharp corners of which are set from the draught of the knife, as it is drawn, till with sufficient pressure for them to cut off the steel in their snappings from the sides of the edge of the knife, rendering sharp as required.

What I particularly claim in this instrument, as my invention of discovery, is the form of the sharpener for the aforesaid purpose, being the circular holes requiring but little space or room, easy to be retained, & trifling in expense, & still sufficient to claim, as my right of invention, the fixing connections, & attaching of the sharpener to the carving fork or any other edge thereof either for the double purpose of a hand sharpener, or for the single purpose of a dresser.
